UNITED STATES PATENT OFFICE.

ARTHUR B. MILLARD, OF TOPEKA, KANSAS.

DESIGN FOR A DECORATIVE GLASS PANEL FOR AUTOMOBILE WINDOWS OR THE LIKE.

Application filed September 22, 1924. Serial No. 10,865. Term of patent 3½ years.

To all whom it may concern:

Be it known that I, ARTHUR B. MILLARD, a citizen of the United States, residing at Topeka, in the county of Shawnee and State of Kansas, have invented a new, original, and ornamental Design for Decorative Glass Panel for Automobile Windows or the like, of which the following is a specification, reference being had to the accompanying drawing, forming part thereof.

Fig. 1 is a face view of a decorative panel of my design.

Fig. 2 is an edge view.

I claim:

The ornamental design for a decorative glass panel for automobile windows or the like, as shown.

ARTHUR B. MILLARD.
